UNITED STATES PATENT OFFICE.

ARTHUR HUGO MÜLLER, OF BLANKENESE, NEAR HAMBURG, GERMANY.

PLANT FOR TOWING VESSELS OR SHIPS ON WATERWAYS.

Application filed September 4, 1924. Serial No. 735,934.

To all whom it may concern:

Be it known that I, ARTHUR HUGO MÜLLER, citizen of Germany, residing at Blankenese, near Hamburg, Germany, Biskupistrasse 9, have invented certain new and useful Improvements in a Plant for Towing Vessels or Ships on Waterways, of which the following is a specification.

The present invention refers to plants for towing ships or vessels on a water way by the aid of a trolley running along an overhead track and supported by an oscillatory frame on the vessel. An oscillatory frame of this description must be adapted to oscillate not only in vertical direction but also laterally within certain limits, so as to avoid unusual forces or strains, which may arise owing to movements of the vessel relatively to the track, and which might destroy or injure the machine or the wire-system carrying the track. A completely floating or free movability in vertical direction is detrimental to the quiet operation of the gearing owing to the wavy repetitions of the slack or sag of the chain-like track, and particularly owing to the unavoidable fluctuations of the drawing power, its vertical component as far as it is not outbalanced by counter weights has the effect that there is a great strain on the track. More particularly when starting the ship and when the oscillatory frame is standing nearly upright a very heavy burdening and even deformation of the track will occur by the incidental great pulling power of the electro-motor that cannot sufficiently be counteracted by change of the momentum of the counter weight.

To avoid these difficulties according to the present invention the free movability of the oscillatory frame carrying the trolley is restricted in vertical direction to a certain extent in such way, that the wavy up-and down-movement are retarded by an elastic resistance that can be easily regulated. This resistance has the tendency to hold the trolley or gearing constantly at the same height without preventing a certain up- and down-movement but which can be increased in starting or stopping the vessel to such an extent, that the free movability of the oscillatory frame can be completely checked.

Devices which answer this object are shown in the accompanying drawing.

Fig. 1 is a diagrammatical elevation of the towing machine adapted to be mounted on board of a ship.

Fig. 2 is an elevation of a modification, and

Fig. 3 an elevation of another modification.

The trolley 1 adapted to run along the track 2 is linked at 4 to the oscillatory frame consisting of arms 5 and 6, which are pivoted to a bracket 7, adapted to rotate about a vertical axis. Thus the oscillatory frame can oscillate in vertical direction as well as to either side. In any position the trolley or driving mechanism 1 is relieved or balanced by the weight of the electro-motor 13 with the gearing 19 and the counter weight 10. The arms 5 and 6 as well as the arm 12 are rotatable about the axis 14. The arm or frame 12 has a triangular shape the top of which is connected to the arm 6 by a rod 20, all these parts constituting together the said oscillatory frame adapted to oscillate about 14. The rod 20 is provided with an adjusting device 24 by the adjusting of which the angle of the arms 5 and 6 with regard to the horizontal plane can be altered. The gear 19 operates by the aid of the shaft 21, the bevel gearings 22, the shaft 17 journaled in the arm 6 and the bevel gearings 23 of the driving mechanism 1, and moreover the motor is also adapted to operate the adjusting device 24. By the aid of the latter the rod 20 can be given a pull, and thereby the angle between the arms 5 and 6 and the arm 12 can be changed.

The arms 5 and 6 serve as links to hold the driving mechanism 1 parallel to the vessel.

To influence the play of the oscillatory frame in the vertical plane between the arm 12 and the rotatable bracket 7 one or more fluid brakes are interposed. Such a fluid brake is constituted by the cylinder 9 mounted rotatably at 7 on a shoulder of the bracket 7 in such way that it can oscillate in a vertical plane similar to the oscillatory frame 5, 6 and the piston rod 8 is linked to the arm 12 at 1. When now the driving mechanism 1 alters its vertical position with regard to the vessel the piston within

the cylinder will be reciprocated. The brake fluid within the cylinder will escape from in front of the piston by the circuit pipe h and enter again the cylinder behind the piston. When the circuit is hindered or completely prevented by more or less closing the valve l also the movement of the piston h and thus that of the oscillatory frame 5, 6 is hindered or prevented.

10 In order to make the braking elastic to the desired extent, at the top of the circuit pipe h on both sides of the valve l a small tank m is arranged, which is only partly filled with brake fluid, but above which there is air thus forming an air tank. The air within these tanks forms an elastic cushion or buffer, as is well known in the common air vessels, but also serves for allowing for differences in temperature of the brake fluid. These air tanks are connected by a valve n, o within the circuit pipe and the atmosphere respectively.

Instead of fluid brakes of course as well 25 pneumatic brakes or friction brakes can be applied. The elasticity can be by way of example obtained by elastic rods, however, the fluid brake has the advantage of greater simplicity and regularity.

The brake can also be used in any other 30 connection between ship and driving mechanism which is freely movable in vertical direction, that is to say it is not limited merely to the use of the oscillatory frame.

The constructions shown in Figs. 2 and 3 35 have the advantage that the driving mechanism running along the track is so yieldingly supported on the vessel, that slight variations in the distance between ship and trolley can be automatically outbalanced but 40 that greater changes in the distance will be overcome by a special adjusting device.

The trolley or driving mechanism 1 running along the track 2, which of course, as in the construction described above, can be 45 used as a drawing trolley, as well as a checking trolley, is here also guided parallelly by the oscillatory frame with the bracket 7 rotatable about a vertical axis. The position 50 of the driving mechanism or trolley with regard to its height is dependent on the length of the stay rod 25, which connects parts of the parallel oscillatory frame 5, 6 diagonally, so as to determine its shape. The length of 55 the rod 25 can be varied. In the construction shown in Fig. 2 the adjustment of this rod can be obtained by a turn buckle 26, and in the construction shown in Fig. 3 by an hydraulic lifting appliance. The rod 25 having at its end a piston h' can be reciprocated in the cylinder i' filled by a suitable fluid, for instance glycerine, and pivoted rotatably at h' on the bracket 7. The piston h' can be reciprocated within the cylinder i' by the fluid in the circuit pipe l' moved from 60 in front of the piston to the back of the pis-

ton. When the valve m' is opened the driving mechanism will be lowered by its own weight and by shutting up the circuit the driving mechanism is held at the adjusted position. When the driving mechanism is to 70 be raised fluid must be pressed into the cylinder i' , for instance by the pump n' . The work necessary for this operation however is so great that in the proper moment the operator cannot carry it out by hand. In 75 order to save mechanical power for the pump the pressure pump n' is not allowed to operate the circuit pipe l' directly but first on an air tank o' , in which a pressure can be created, the fluid being taken from a balancing 80 tank p' . When in case of need the valves q' and r' are opened, the compressed air within the tank o' will press the fluid into the cylinder i' thus forcing the piston h' to move in the desired direction, while from the other side of the piston the fluid is allowed to escape to the balancing tank p' . In this way power is accumulated in the most simple manner enabling the operator to carry out this work at leisure time, so as to have 85 the necessary pressure at hand in case of need.

The simple adjusting device as described above can be combined with an elastic checking or retarding of the vertical movement of 90 the driving mechanism. In this instance it is only necessary to arrange in front of the circulating pipe l' and behind the valve m' further small air tanks s' and t' which act as a buffer in all unforeseen movements of 100 the piston h' . Since one of these air tanks s' is always under pressure created by the weight of the driving mechanism, it will be first necessary to fill it as well as the tank o' with a certain amount of air, so as to create 105 the necessary pressure by the aid of a suitable pump u' , while the other tank t' need only contain a little air of atmospheric pressure.

In the construction shown in Fig. 2 a 110 spring 27 is used instead of the pneumatic buffer arrangement for sake of simplification. This spring buffer need of course not be directly pressed within the stay rod 25 but may as well be arranged in the driving 115 mechanism 1 or in the oscillatory frame 5, 6 or in the rotatable bracket 7 and its connection. The construction shown in the drawing has the advantage of greater simplicity and also guarantees the vertical guidance of the driving mechanism 1. To prevent the ship from pressing against the track 2 owing to inadvertancy of the operator or crew in operating the adjusting device the diagonal rod 25 will not be made rigid but 120 in sections and the two sections connected elastically or connected by a link 28.

By these devices slight alterations in the height of the driving mechanism 1 can be 125 automatically outbalanced, while greater al- 130

terations, which for instance will be necessary in passing bridges or locks, can be carried out by the aid of the adjusting device.

I claim:

5 1. The combination with a vessel of a trolley adapted to run along an overhead track and mounted floatingly on the vessel, means to automatically balance the trolley as to its height to account for fluctuations 10 in the height of the track and means to retard the vertical movements of the trolley.

2. The combination with a vessel of a trolley adapted to run along an overhead track, an oscillatory frame carrying said 15 trolley and mounted rotatably on the vessel, means to automatically change the angle of the said oscillatory frame to the horizontal and means to retard the vertical movements of the trolley.

20 3. The combination with a vessel of a trolley adapted to run along an overhead track, an oscillatory frame carrying said trolley and mounted rotatably on the vessel, means to automatically change the angle of 25 the said oscillatory frame to the horizontal and a fluid brake to retard the vertical movements of the trolley.

4. The combination with a vessel of a trolley adapted to run along an overhead track, an oscillatory frame carrying said trolley and mounted rotatably on the vessel, means to automatically change the angle of the said oscillatory frame to the horizontal and a fluid brake to retard the vertical movements of the trolley, a circuit pipe in which 30 the fluid brake is interposed and an air tank communicating with the circuit pipe and adapted to act as an elastic buffer.

5. The combination with a vessel of a trolley adapted to run along an overhead track an oscillatory frame carrying said trolley and mounted on the vessel, means to 35 automatically carry out slight changes of the angle of the said oscillatory frame to the

horizontal and means to carry out considerable changes of the angle of that part of the oscillatory frame carrying the trolley. 45

6. The combination with a vessel of a trolley adapted to run along an overhead track, an oscillatory frame carrying said 50 trolley and mounted on the vessel, means to automatically carry out slight changes of the angle of the said oscillatory frame to the horizontal and means to carry out considerable changes of the angle of that part of 55 the oscillatory frame carrying the trolley, and means to retard the movements of the trolley when carrying out the said changes of the angle.

7. The combination with a vessel of a trolley adapted to run along an overhead track, an oscillatory frame carrying said 60 trolley and mounted on the vessel, means to automatically carry out slight changes of the angle of the said oscillatory frame to 65 the horizontal and means to carry out considerable changes of the angle of that part of the oscillatory frame carrying the trolley, comprising an hydraulic cylinder, a piston and a piston rod forming part of the oscillatory frame. 70

8. The combination with a vessel of a trolley adapted to run along an overhead track, an oscillatory frame carrying said trolley and mounted on the vessel, means to 75 automatically carry out slight changes of the angle of the said oscillatory frame to the horizontal and means to carry out considerable changes of the angle of that part of the oscillatory frame carrying the trolley, comprising an hydraulic circuit-pipe, an hydraulic cylinder communicating with said 80 circuit-pipe, a piston and a piston rod forming part of the oscillatory frame and an air tank communicating with the circuit-pipe 85 and forming a pneumatic buffer.

ARTHUR HUGO MÜLLER.
